UNITED STATES PATENT OFFICE.

CHARLES KEEN, OF ST. LOUIS, MISSOURI.

CONVEYER.

1,096,509.

Specification of Letters Patent. Patented May 12, 1914.

Application filed August 3, 1911. Serial No. 642,141.

To all whom it may concern:

Be it known that I, CHARLES KERN, a citizen of the United States of America, residing in the city of St. Louis and State of Missouri, have invented certain new and useful Improvements in Conveyers, of which the following is a specification.

This invention relates to conveyers in general, but more particularly to conveyers adapted to transport the products of a bakery from a baking floor to a packing floor, and has for its primary object to provide an improved construction, combination and arrangement of parts in devices of this character.

One of the objects of the present invention is to provide improved means for stacking and loading the goods onto the conveyer.

A further object is to provide improved means whereby the conveyer will be automatically stopped for loading.

Another object is to provide, in combination with the aforesaid conveyer, improved means for unloading the wares therefrom while in motion, and for conveying said goods away from the point at which they are unloaded.

Another object is to provide an improved timing device for governing the relative successive movements of a pair of intermittently movable conveyers.

Another object is to provide improved means for starting the conveyers after they have been brought to rest.

With these and other objects in view, as will appear in the specification and on the drawings forming a part thereof, my invention consists in the various combinations and arrangements of parts set forth in the appended claims.

In the drawings: Figure 1 is a side elevation of the upper end of my improved device. Fig. 2 is a side elevation of the lower portion of the same. Fig. 3 is a top plan view of the portion shown in Fig. 1. Fig. 4 is a front elevation of the stacking and loading devices, parts being shown in section, and parts being broken away. Fig. 5 is an enlarged detail section on the line V—V, Fig. 4. Fig. 6 is a similar view, showing the parts in shifted position. Fig. 7 is an enlarged fragmentary vertical section through the rear end of the lower portion of the machine shown in Fig. 2, illustrating the unloading operation. Fig. 8 is a section on the line VIII—VIII, Fig. 3. Fig.

9 is an enlarged detail section on the line IX—IX, Fig. 3. Fig. 10 is an enlarged detail section on the line X—X, Fig. 1. Fig. 11 is a fragmentary top plan view of portions of the stacking and loading device. Fig. 12 is an enlarged detail section on the line XIII—XIII, Fig. 6. Fig. 13 is a fragmentary detail section on the line XIII—XIII, Fig. 11. Fig. 14 is an enlarged detail section on the line XIV—XIV, Fig. 3. Fig. 15 is an enlarged detail section on the line XV—XV, Fig. 1. Fig. 16 is an enlarged fragmentary detail section on the line XVI—XVI, Fig. 2 with the conveyer pan shown to the right of said line in lowered position. Fig. 17 is a section on the line XVII—XVII, Fig. 15.

Referring more particularly to the drawings in which my invention is exemplified in its adaptation to the conveying and packaging of crackers, and first of all to Figs. 1 and 2 of said drawings, my invention contemplates a stacking and loading device; a vertically movable conveyer; a horizontally movable conveyer working in conjunction with the first said conveyer; a timing device or governor for controlling the relative operations of the conveyers; and an unloading device. These several parts of the machine will be described separately.

Stacking and loading device.—Referring to Figs. 1, 3 to 6, and 9 to 14, a feed table 1, which may be rigidly mounted in any suitable manner but is preferably secured to the structural work forming the conveyer shaft to be hereinafter referred to, is supported by struts 2. Said table, as shown best in Figs. 5, 9 and 10, comprises a bottom pan with a laterally turned flange 3 on either side, and an angle iron 4 secured to the flange 3. Swingingly connected with the forward edge of the table 1 by means of hinges 6 is a bridge plate 7 for bridging the gap between the table 1 and each of the conveyer trays to be referred to hereinafter.

On the horizontal flange of each angle bar 4 is slidably mounted a carriage block 8 which is provided with an inner depending guide flange 9 and an outer depending flange 10 from which project journal pins 11 for journaling the rollers 12 which serve to retain the carriages 8 against upward displacement when they are operated in a manner to be presently described. Projecting upwardly from the carriage 8, are a pair of bearing lugs 13 within which is secured an

elongated bearing pin 14, said pin being extended laterally and engaging in a slot 15 in the upper end of each arm 16 of a bifurcated throw lever; said throw lever (as shown best in Figs. 1 and 4) having its stem portion 17 swingingly mounted upon a bolt 18 carried by the lower ends of a pair of brackets 19. The stem 17 of the throw lever is centered between the brackets 19 by means of sleeves 20.

Referring more especially to Figs. 3, 11 and 13, a stacking frame is pivotally connected with the carriages 8, and comprises a front rail 21 and side rails 22, each of said side rails being pivotally mounted on one of the pins 14. Rigidly mounted adjacent one of the side rails 22, is a rod or bar 23 upon which is swingingly mounted a stacking gage comprising an upright 24 with its bearing arms 25, said gage being adapted to be thrown over into the position shown in dotted lines in Fig. 9 for a purpose to be hereinafter explained. Each of the arms 16 of the throw lever is provided with a lug 26 on its outer face, upon which is pivotally mounted a hand lever 27, each of said levers conforming to the upper ends of the branches 16 of the throw lever, so that when shoved forwardly they abut against said branches 16 and are adapted to produce a forward movement of the throw lever. A retaining band or strap 28 serves to limit the rearward movement of each hand lever 27.

As shown best in Figs. 3 and 5, each hand lever 27 is provided with a pivotal support 29 for one arm 30 of a pusher, said pusher being provided with a front plate 31 with its lower edge sliding along the rim of the table 1. In order to make it convenient for handling large slabs of separable units, a slidable extension 32 is (as shown in Fig. 14) resiliently mounted on the end face of a table 33 having a depending apron 34. For this purpose pins or rivets 35 slidably retain the extension 32, said extension being provided with a pair of slots 36 for receiving the pins 35. A bow spring 37 (see dotted lines Fig. 3) is secured to the extension 32 by means of brackets 38, the curved extremities of said spring being in abutment with the inner wall of the apron 34, so that any lateral displacement of the extension 32 is resisted and said extension caused to return to normal position as soon as the pressure is removed. As shown in Fig. 3, the extension 32 is provided with an inclined rear edge 39 adapted to receive a displacing pressure from the upper end of the right-hand branch of the throw lever.

A mechanism for effecting the return movement of the stacking frame without interference with the stacked goods, which have been pushed forward onto the conveyor pan, will now be described. Journaled

within brackets 40 (see Figs. 1, 3 and 5) is a rocker shaft 41. Rocker arms 42 have their hubs 43 keyed to the rocker shaft 41 in any suitable manner. The forward ends of said rocker arms 42 are provided with slots 44, within which (as shown best in Fig. 12) slides a pin 45 projecting from the boss 46 at the lower end of a plunger 47 which is reciprocable within a sleeve 48. Whenever these plungers 47 are in raised position, as shown in Figs. 6 and 12, that is, when the stacking frame is in its forward position, the upper ends of said plungers impinge upon the lower edges of the side rails 22 of said frame and elevate them into the positions shown in Fig. 6, in which position the frame is free to enter upon its return movement without engaging the stacked goods over which it travels.

Normally, when the parts are in the position shown in Fig. 5, a cross bar 49, which extends between the forked arms 16 of the throw lever, is resiliently engaged by a leaf 50 having a deflected end 51 for limiting the rearward movement of the throw lever. Said leaf 50 is rigidly connected to the rock shaft 41, and is preferably integrally formed with a latch bar 52, which depends from the rock shaft 41 and is connected to said shaft by means of a set screw 53. Projecting rearwardly from an angle bar 54, which is rigid with the conveyor through-way construction, is a bowed spring leaf 55 with its rear end suitably formed at 56 to resiliently engage the lower end of the bar 52. Reciprocably mounted on the bar 52, is a latch 57 provided with a cam 58 adapted to be engaged by the cross bar 49 when the throw lever is forced into forward position. Said latch 57 may be conveniently mounted by means of pins or bolts 59 sliding in slots 60 in the latch 57, the lower end of said latch being in abutment with a shoulder 61 on the end of the spring leaf 55.

Referring now more especially to Figs. 5, 6, 12 and 13, the horizontal flange of the angle bars 4 connected to the side rails of the feed table are provided with slots 62 through which, in normal position of the parts, depend a pair of lugs or blocks 63, said lugs being swingingly mounted on pins 64 with their forward edges abutting against blocks 65 rigid on the side rails 22, said blocks 65 serving to prevent a forward swinging movement of the lugs 63. A coil spring 66 serves to press the blocks 63 against the blocks 65. Other blocks 67, which are secured to the side rails 22 at a distance from the blocks 65 to permit the lugs 63 to swing rearwardly during the forward movement of the stacking frame, serve to support the side rail 68 (see Figs. 11 and 12) for supporting the outer ends of the pins 64.

Referring now to Figs. 1 and 15, on one

of the angle bars 69 of the conveyer framework, is rigidly mounted the bracket 70 which carries a pin 71, upon which is pivotally mounted a plurality of stop arms 72, 73 and 74 of different lengths. These stop arms are adapted to engage a rib 75 extending along the end bracket of each conveyer pan when it stops opposite the feed table 1. These stops are made of different lengths so as to provide for any little discrepancies in the positions which the conveyer pans reach when the conveyer is stopped.

Briefly described, the operation of the stacking and loading device is as follows, when used in connection with goods baked in large layers of connected series of units. The baker having superposed a number of layers of these goods one upon another by the manipulation of a scoop or shovel, drops the pile of heated goods upon the table 1 and extension 32. During this operation, the stop gage 24 serves to align the hot slabs of biscuits or crackers. The gage 24 is then thrown over into the position shown in dotted lines in Fig. 9, thus allowing space for the operator to introduce his fingers for separating the superposed slabs along the weakened lines which divide the adjacent series. Each group of series is stacked on edge parallel to the lateral rails of the stacking frame, and when the pusher 31 is moved forward by means of either handle 27, the stacked groups of series are aligned against the front rail 21 of the stacking and loading frame. By this time, the hand levers 27 have been brought into abutment with the forks of the operating lever, and the mass is moved forward from the feed table 1 within the stacking and loading frame, over the bridge 7 onto the conveyer pan, which happens to be in position for receiving them.

During the forward movement of the throw lever, the cross bar 49, (see Figs. 5 and 6) is moved forward until it impinges the cam 53 and forces the latch 57 downwardly to displace the spring leaf 55 and release the bar 52. Immediately, under the action of the tension spring 76, the bar 52 is drawn toward the conveyer shaft, and the rocker arm 42 is thrown upward to force the plungers 47 into engagement with the side rails 22 of the stacking and loading frame, elevating it into the position shown in Fig. 6. The goods being thus stacked upon the conveyer, the parts are returned to normal position (shown in Figs. 1 and 5) for another load.

As shown best in Figs. 1, 3 and 7, the vertical conveyer comprises a pair of endless chains 77 of any suitable construction, which are suspended from above over the chain sprockets 78 carried by a shaft 79. At the lower end, the forward run of the chain is displaced forwardly and caused to run around a guide sprocket 80 and thence

around a guide sprocket 81 in the rear. This disposition being for the purpose of spacing the conveyer pans horizontally in a manner to be hereinafter more fully pointed out. The conveyer chains thus mounted are adapted to pass upward and downward through a conveyer shaft formed of the vertical angle bars 82 and transverse angle bars 69, the upper portion of said shaft having slidably mounted thereon a head frame 75 which can be raised and lowered by means of vertical adjusting screws 83. This construction being for the purpose of adjusting the tension of the conveyer chains when de- sived.

On the lateral sides of the conveyer shaft, are mounted vertical channels 84 with their channels turned inward and suitably disposed to receive the ends of guide pins 85 (see Figs. 15 and 16), which serve to hold the runs of the chains in proper positions. The pins 85 are preferably formed by extensions to one of the connecting pintles of the chain links in each instance, and serve to swingingly support the hubs 86 of the lateral frames or supports 87 carrying the conveyer pans 88.

Referring now to Figs. 2 and 7, the horizontal conveyer is preferably in the form of the endless band 89 carried by a forwardly flanged pulley 91, said pulleys being connected to shafts 92 and 93 journaled in pedestals 94 and 95 which are mounted on the floor 96 of the shipping room, and are preferably of suitable height to bring the upper fold of the conveyer 89 at a convenient height above the floor to facilitate the packer's handling of the goods as they travel forward on the conveyer. An upright shaft 97 provided with a bevel gear 98 at its lower end serves to transmit power to a bevel 99 on the rear end of the shaft 100, which shaft 100 is provided with a bevel 101 meshing with a second bevel 102 on the shaft 92 for driving the forward pulley 90. The return fold of the conveyer 89 passes about the guide rolls 103 and is supported intermediately of said guide rolls by means of supporting rails 104 mounted in suitable pedestals or supports.

The process of unloading the goods from the vertical conveyer onto the horizontal conveyer is best illustrated in Fig. 7, which shows a forward pan loaded with goods in a slightly elevated position which it occupies when the vertical conveyer is stopped in a manner to be hereinafter point out. This position is determined so as to leave just enough room for the mass of goods 105 (shown in dotted lines) to pass thereunder. Said goods have just been removed from the rear pan, shown in Fig. 7, which is in unloading position in which it is supported just out of contact with the upper fold of the conveyer 89. In this position, the de-

pending plate or pusher 106 of an unloading device has its lower end slightly above the bottom of the conveyer pan, but to insure no positive interference between the parts, said plate 106 is oppositely swung about a pintle 107 in the bearings 108, there being a counterweight 109 on the rearwardly projecting arm 110 tending to hold the plate 106 against displacement rearwardly, so that as the pan travels toward the rear, the goods are shoved off onto the conveyer 89, as illustrated.

In order to prevent sagging of the horizontal runs of the vertical conveyer during the unloading operation, said horizontal runs are slidingly supported by the horizontal flanges of angle bars 111. In order to impart stability to the pans 88, a swinging strut 112 is swingingly mounted on a pintle 113, which is suspended from the under side of the horizontal flange of each of said angle bars 111. Said strut 112 is provided with a counterweight 114 which serves to displace its lower extremity into a position in which it will slidably engage the upper inclined edge of the lug 75 (see Fig. 16). As shown in Fig. 2, the strut 112 is elongated in the direction of travel so as to more effectually support the conveyer pan during its unloading movement. The forwardly traveling fold of the conveyer 89 slides on the slab or table 115 which extends substantially the whole distance between the pulleys 90 and 91, thus serving to hold the conveyer perfectly flat. The forward fold of the vertical conveyer is displaced inwardly by the guide sprockets 116 which are mounted within the conveyer shaft intermediate of the upper and lower ends thereof.

Referring more especially to Figs. 1 and 4, power is conveniently delivered to the conveyer by means of a driven pulley 117 keyed to a power shaft 118, said pulley 117 being adapted to receive its power from any suitable source. Keyed to the power shaft 118, to one side of the pulley 117, is a driven pulley 119 with a broad face upon which runs a belt connector 120 which, when the conveyer is stopped, runs over a loose pulley 121 on the countershaft 122 mounted in bearing brackets 123 carried by the framework.

Keyed to the countershaft 122 is a companion pulley 124 to the loose pulley 121 onto which the belt 120 may be shifted by a reciprocable rod 125 provided with belt shifting prongs 126, said rod 125 being mounted in brackets 127. A link 128, having one end pivotally connected at 129 with the reciprocating rod 125, serves to impart movement to said rod by having its other end connected at 130 with the arm 131 keyed to a shaft 132, which is journaled in the bracket 133. On the other end of the shaft

132 is secured a hand lever 134, upon which is pivotally mounted at 135 a clasp release 136. As shown best in Fig. 17, the hand lever 134 is provided with a forwardly projecting arm 137 upon the outer end of which is a bearing lug 138 for reciprocably mounting a stop bolt 139 which is adapted, when the parts are in the positions shown in Fig. 1, to intercept the guide pins 85 carried by the conveyer chains.

The operation of this portion of the device will now be readily understood, and briefly stated, is as follows: When the vertical conveyer is at rest, as shown in Fig. 1, the belt 120 runs on the loose pulley 121, no motion being transmitted to the countershaft 122. When the tray has been loaded, the operator grasping the hand lever 134 and pressing thereto the clasp release 136, simultaneously withdraws the bolt 139 out of engagement with the pin 85 and shifts the bar 125 to throw the belt 120 on the tight pulley 124. Immediately, power is transmitted to the countershaft 122 and the machine is driven by means of those portions now to be described. For this purpose, a pulley 140, which is keyed to the shaft 122, imparts its motion to a belt 141, which in turn drives a pulley 142 keyed to a worm shaft 143 journaled in hangers 144 which depend from the top frame of the structure. Keyed to the shaft 143 is a worm 145 which meshes with a worm wheel 146 keyed to a power transmitting shaft 147 which is journaled in bearing blocks 148, (see Fig. 3). As shown clearly in Figs. 3 and 8, a mutilated gear 149 is also keyed to the shaft 147 and is provided with gear teeth 150 for approximately one-half of its circumference. Keyed to the front shaft 151, which is journaled in bearing brackets 152, is a gear 153 which is rotated one-half of a revolution every time the mutilated gear 149 rotates. The shaft 151 is connected by bevel gears 154 to the upright shaft 97, which delivers power to the horizontal conveyer in the manner already pointed out. A large gear 155 keyed to the end of shaft 79 upon which the chain bearing sprockets are carried also meshes with the teeth 150 on the mutilated gear, being rotated one-fourth of a revolution for each rotation of the gear 149.

To insure the proper starting of the gears 153 and 155, after each period of rest, said gears are provided with offset gear tooth fingers 156 which are spaced to correspond to the revolutions of said gears. In order, however, to insure a positive interlocking connection, these gears of the governing device, a beam 157 is mounted from an I-bracket 158 to swing about an axis 159, said beam being provided at opposite ends with toes or cogs 160 and 161, which cogs are adapted to mesh alternately into grooves or sockets 162 formed in the peripheries of the 136

locking disks 163 and 164 which are keyed to the shafts 151 and 79, respectively. The beam 157 is automatically locked in either position in which it happens to be in the manner now to be pointed out.

While the parts are in the position shown in Fig. 8, the periphery of the lock disk 163 will prevent any change in position of the beam 157 after the notch 162 has passed out of register with the tooth 160. In the same manner when the tooth 160 is forced into a notch in the disk 163, the periphery of the disk 164 will maintain it in that position. Normally, the beam 157 tends to assume the position shown in Fig. 8, for which purpose means for drawing the right-hand arms downwardly is provided by a weight 165 suspended by a link 166 from said arm. Under the action of this weight, when the mutilated gear 149 has just completed a quarter rotation of the gear 155, and passed out of mesh, the tooth 161 on the left-hand end of the arm 157 registers with a notch 162 in the disk 164 whereupon the weight 165 forces the tooth 161 into said notch and the disk 163 is released and the motion of gear 149 is imparted to gear 153 to drive the lower conveyer in the manner already pointed out.

As the rotation of the mutilated gear 149 continues, a pin 167 which projects laterally therefrom, is brought into engagement with the end of a lever 168, which is provided with a journal pin 169 oscillatably mounted in a pedestal 170. Adjacent the outer end of the lever arm 168 is pivotally connected the upper end of a connecting link 171, said link being pivotally connected at 172 with the right-hand arm of the beam 157. When, therefore, the pin 167 impinges the end of the lever 168, which engagement occurs after the gear 153 has been rotated one-half of a revolution, the tooth 161 is forced downwardly to release the gear 155, and the tooth 160 is forced upwardly to engage the disk 163. By means of this construction, motion is imparted in successive stages to both the vertical conveyer and the horizontal conveyer, the vertical conveyer being left at rest for the loading operation, as shown in Fig. 1, and being in motion for the unloading operation, as is shown best in Fig. 7. On the other hand, by means of this gearing and the relative position of the parts of the conveyer, the vertical conveyer is in loading position and held stationary just subsequent to the unloading of the conveyer pan, as shown in Fig. 7, the right-hand loaded pan being therefore suspended stationary to permit the goods 105 to pass thereunder without interference.

Should it be desired to have the vertical conveyer automatically set in motion by the loading movement, means are provided whereby this may be done. For this pur-

pose, a lever arm 173 may be keyed to the shaft 18, to which the throw lever 17 is also keyed. Secured to the forward end of the lever arm 173 is a cable 174 which passes upwardly over a pulley 175 carried by a bracket 176; said cable being secured to the extremity of an offset portion 177 of a rocking lever 178. Said rocking lever is pivoted at 179 within a bearing block 180, and is provided with a projection 181 between which and a projection 182, on the framework, is provided a tension spring 183 for imparting a normal tendency to hold the rocking lever 178 in the position shown in Fig. 1. The lever 178, as shown best in Fig. 4, is adapted to impinge directly upon the clasp release 136 so that when the throw lever 17 is thrown forward, the arm 173 draws down upon the cable 174 and throws the lever 178 against the clasp release 136 to operate it in the manner already pointed out.

A peculiar advantage resides in the time mechanism control of the vertical and horizontal conveyers, in that while the vertical conveyer is traveling a distance equal to the space between two pans, one of the pans is being unloaded and another is being brought into position to be loaded. Immediately after this intermittent movement of the vertical conveyer, it is held stationary during the loading movement while at the same time the horizontal conveyer makes a forward movement to carry the unloaded crackers out from underneath the next loaded pan. During this forward movement of the horizontal conveyer, the pan which is being loaded is held stationary until after the stacking and loading frame has been retracted, when the vertical conveyer is free, to make a further movement.

What I claim is:

1. The combination with a loading table, of a stacking frame, a throw lever operatively connected to said stacking frame, a hand lever movably connected to said throw lever to permit an initial movement independently of said throw lever, and a pusher operatively connected to said hand lever.

2. In a device of the character described, the combination with a conveyer provided with a pivotally mounted carrier, of a loading table, means for arresting the movement of said carrier opposite said table, and means for supporting said carrier against tilting while it is at rest, said means comprising a projection on said carrier, and a plurality of stops of different lengths adapted to singly engage said projection.

3. The combination with a stacking and loading frame, of a pusher co-operating therewith, and means for reciprocating said frame and pusher together said pusher being movable independently of said frame to evenly stack the goods therein contained.

4. The combination with a loading table,

of a stacking frame comprising lateral rails and a front rail, a stacking gage swingingly supported from without said stacking frame and adapted to be removably disposed within one of said lateral rails, a throw lever connected to said stacking frame, a hand lever movably connected to said throw lever to permit an initial movement independent of said throw lever, and a pusher connected to said hand lever whereby it may be moved along said stacking gage.

5. The combination with a feed table, of carriages reciprocable thereon, a loading frame comprising side rails pivoted at one end to said carriages, respectively, plungers reciprocably mounted in said table with their extremities normally below said side rails, and means operable at the end of the forward stroke of said frame for lifting said 15 plungers to slidably support said side rails above the table on the return stroke.

6. The combination with a loading table, of a stacking frame reciprocable thereon, a throw lever connected to said frame, and a pusher movable relatively to said frame, and means connecting said pusher to said throw lever whereby said pusher is moved prior to said frame.

7. The combination with a loading table provided with lateral flanges, of carriages reciprocable on said flanges, a stacking frame comprising lateral rails pivotally connected to said carriages, and a front rail slidably engaging said table, and a throw lever connected to said carriages.

8. The combination with a loading table provided with lateral flanges, of carriages reciprocable on said flanges, a stacking frame comprising lateral rails pivotally connected to said carriages, a front rail slidably engaging said table, a throw lever connected to said carriages, a hand lever movably connected to said throw lever to permit an initial movement independently of said throw lever, and a pusher connected to said hand lever and projecting between said lateral rails of the stacking frame.

9. A loading device comprising a table, a stacking and loading frame mounted on said table, and a pusher operatively related to said frame, said pusher being movable independently of said frame to evenly stack the goods therein contained.

10. The combination with a feed table, of a loading frame reciprocable thereover, of a plunger adapted to elevate said frame, means tending normally to operate said plungers, a latch mechanism for holding the last said means inoperative, and a throw lever for said frame; said throw lever being adapted to engage said latch mechanism to release the plunger operating means.

11. The combination with a table, of a loading frame reciprocable thereon, a pivotally mounted block carried by said frame

to drag over the table during the forward movement, means for elevating said frame at the end of its forward movement, and means for holding said block in a position to maintain the frame in elevated position during its return movement.

12. The combination with a loading table provided with up-turned edges, of a reciprocable pusher movable parallelly to said edges, and a spacing device adjacent one of the up-turned edges.

13. The combination with a table, of a stacking gage adjacent one edge of said table, and means for imparting a forward movement to the material along said stacking gage; said gage being pivotally mounted to permit it to be swung out of the way during the loading movement.

14. In a device of the character described, the combination with a vertical conveyer having a horizontal run, of a horizontal conveyer, carriers pivotally mounted on said vertical conveyer; said carriers being moved in close juxtaposition to said horizontal conveyer during their horizontal movement; and means for removing goods from said carriers; said means comprising a pusher depending in the path of said carriers during their horizontal movement; said pushers being pivotally supported above and provided with a counterweight tending to hold it against movement in the direction of said carriers.

15. The combination with a conveyer comprising spaced endless chains with a horizontal run, carriers having side frames pivotally swung from said chains of means for unloading said carriers; said means comprising a pivotally mounted plate intermediate of said chains; said plate being provided with a counterweight to resist a swinging movement in the direction of travel of said carriers.

16. In a device of the character described, the combination with coöperating conveyers, of adjacently disposed shafts for respectively driving said conveyers, gears carried by said shaft, a mutilated gear whereby said gears are driven alternately, a notched disk carried by each shaft, and a pivotally mounted beam provided with a tooth at each end; said beam being adapted to alternately block said disks.

17. In a device of the character described, the combination with coöperating conveyers, of adjacently disposed shafts for respectively driving said conveyers, gears carried by said shaft, a mutilated gear whereby said gears are driven alternately, a notched disk carried by each shaft, a pivotally mounted beam provided with a tooth at each end; said beam being adapted to alternately block said disks; and means tending normally to hold said beam from contact with one of said disks.

18. In a device of the character described, the combination with coöperating conveyers, of adjacently disposed shafts for respectively driving said conveyers, gears carried by said shaft, a mutilated gear whereby said gears are driven alternately, a notched disk carried by each shaft, a pivotally mounted beam provided with a tooth at each end; said beam being adapted to alternately block said disks; and means operated by said mutilated gear for shifting said beam.

CHARLES KERN.

In the presence of—
AUGUST KAMINSKA,
H. G. FLETCHER.
